UNITED STATES PATENT OFFICE

2,446,340

SPEED DENSITY CARBURETOR

Andrew William Orr, Jr., Detroit, Mich., assignor
to George M. Holley and Earl Holley

Application March 9, 1946, Serial No. 653,358

7 Claims. (Cl. 123—119)

1

The object of this invention is to proportion the fuel to the air in an internal combustion engine. Specifically, the object is to control the fuel flow by: (a) the velocity of flow of the fuel to the engine; (b) the speed of the engine; (c) the pressure of the air entering the engine (Manifold air pressure); (d) means responsive to the temperature of the charge to control the fuel; (e) means responsive to the back pressure of the exhaust to control the fuel; (f) to provide automatic means for controlling the low speed fuel flow.

This application is a continuation in part of my co-pending application Serial No. 646,559 filed February 9, 1946.

The figure shows the preferred form of my invention.

In the figure, 10 is the fuel entrance, 12 is the shaft, driven by the engine at engine speed or at some speed proportional to engine speed, which drives a vane pump 14, which delivers fuel under pressure to a passage 26. The pressure generated by this pump is regulated by the centrifugal governor comprising the shaft 16, balls 18 and discs 20—22. The annular diaphragm 24 allows fuel to escape from passage 28 past the pressure relief valve 34, through 36, back to the fuel entrance 10. A diaphragm 33 and spring 41 and passage 42 cooperate to apply a load to the valve 34.

The fuel flows through a fuel venturi 48, the fuel follows the path, through the passage 76, past the valve 78, to exit passage 80, and then flows past the equalized valve 104. The valve 104 is supported by the diaphragm 92. A compression spring 102 supports the diaphragm 92 so as to open the valve 104 in response to the pressure in the chamber 90, which pressure acts to supplement the compression spring 102. A second diaphragm 270 is added, plus a second compression spring 272.

The chamber 302 is formed between the diaphragms 92 and 270. This chamber 302 is connected by the pipe 98 with the restriction 100. The restriction 100 is connected to the chamber 30. Hence, a relatively low pressure sometimes is established in the chamber 302. When a low pressure exists in the chamber 302, a spring 272 plus whatever pressure there may be in chamber 304, is applied to the diaphragm 92 and thus is applied to the balance valve 104. The chamber 304, located above the diaphragm 270, is connected through the pipe 300 with the air entrance passage 112. When the pressure in the chamber 98 rises, the diaphragm 270 is raised

and the compression spring 272 ceases to have any influence on the valve 104. The valve 104 is then moved down by the high pressure in the chamber 302 compressing the spring 102.

5 The balanced valve 65 guided on the cylinder 66 admits fuel through the passage 68 to join the fuel passing through the passage 80. The pressure pipe 74 is connected from the outlet 26 from the pump 14 to the chamber 72 behind the 10 diaphragm 64 which is pushed to the left by the spring 196.

15 The diaphragm 46 responds to a compression spring 103, acting in opposition to the depression created in the throat of the venturi 48. This 20 depression acts in the chamber 50, but this pressure in the chamber 50 is slightly higher than the pressure in the venturi 48. A restriction 250 regulates the pressure in the chamber 50. A pipe 252 communicates with the chamber 50 and with 25 a manually-controlled valve 254, which is controlled by a lever 288.

25 In the position shown in the drawing, the valve 254 is shown in the automatic rich (A. R.) position. In this position (A. R.), pipe 252 is in communication with the pipe 256 through an opening 258 in the valve 254. The pipe 256 communicates with the downstream side of the venturi 48 through a restriction 260, so that the pressure in the chamber 50 is slightly greater than the 30 pressure in the throat of the venturi 48. Diaphragm 46 and the needle valve 56 control the flow of fuel through a passage 58, this fuel flows directly through the valve 254 to the restricted passage 264 to the chamber 62 to the right of the diaphragm 64, which diaphragm is to the 35 right of chamber 72, which chamber communicates with the pressure pipe 74 as already stated.

When the lever 288 moves anti-clockwise 40 slightly less than 45° the pipe 58 is put in communication with both the restricted passages 264 and 265. At the same time the passages 256 and 252 are no longer in communication with each other so that the pressure in chamber 50 is equal to the depression in the throat of the 45 venturi 48.

The lever 288 is connected through the link 350 with a corresponding lever 188. The lever 188 is connected to a valve 184 which controls the flow through a pipe 98. In the A. R. position 50 in which the valve 184 and 254 are shown fuel can not flow through the pipe 98 and can not flow through the valve 184 because the port 182 does not connect the passage 98 with the passage 388, which passage 388 is connected through 55 the passage 146 to the pump outlet passage 26.

The temperature bulb 144 is connected through the pipe 148 to the elements 150, which control the valve 284. This valve 284, at high temperature moves down and allows the fuel pressure existing in 26 to be applied through the passage 490 to the passage 500 to the pipe 98 to the space 302 between the two diaphragms 92 and 270 and thus restricts the fuel flow. Pressure in this space 302 between diaphragms 92 and 270, when the lever 188 is in the A. R. position and when the temperature is cold, is determined by the pressure to the right of the diaphragm 24 because of the restricted connection 100. Element 130 is connected to the exhaust back pressure and is connected in series with the elements 128 which are evacuated and located in the chamber 124 connected through passage 122 to the supercharger outlet 140.

The valve 78, which is the main fuel control of the carburetor, is moved to the right by an increase of pressure in the supercharger outlet 140 acting on the element 122. The valve 78 is moved to the left by an increase in exhaust back pressure acting in the element 130. The flow past the valve 78 depends on the position of the valve 78 as thus determined, and on the pressure drop from the fuel entrance 76 to the fuel exit 80. This passage 800 is normally closed by the extension of the valve 78. When the valve 78 moves to the left an annular port 278 opens the bypass 800. An adjustable needle 13 regulates the low speed flow of fuel through the passage 11 and this fuel flows past the valve 104.

The fuel is discharged through a passage 600 past the fuel outlet nozzle 108 which allows the fuel to discharge into the passage 700 downstream from the throttle 119.

A pipe 410 connects the chamber 124 with a chamber 420 which contains the temperature responsive element 150. A chamber 430 contains a spring 440 which opposes the downward movement of the valve 284. A passage 450 connects the chamber 420 with the chamber 430. A chamber 460 contains a compression spring 470. The compression spring 470 opposes the movement to the left of the valve 78. A passage 480 connects the chamber 124 with the chamber 460.

Low-speed operation

In the low-speed operation, the throttle 119 approaches the closed position, the supercharger 120 no longer creates a pressure, and the pressure outlet 140, and therefore the pressure in the passage 122 and the pressure in the chamber 214, becomes less than atmospheric pressure. Valve 78 moves over to the left and valve 278 permits a small quantity of fuel to flow to the low-speed passage 11, past the needle valve 13. When the lever 288 and when the lever 188 are moved anti-clockwise about 90° into the idle cut off position, fuel is prevented from running out of the system, that is to say, it is trapped in the system because pressure in the pipe 98 becomes equal to the pressure in the passage 146 which is equal to the pressure created by the fuel pump 14. Therefore the pressure in chamber 302 becomes great enough to cut off the flow of fuel through the pipe 600 by pushing the valve 104 down.

Normal operation

In the position in which the elements are shown, which is the automatic rich position, valve 184 has no function, and assuming the engine is cold valve 284 has no function because it rises and prevents communication between the pas-

sage 400 and the passage 500. The relatively low pressure in the chamber 30 is then transmitted through the restriction 100, through the passage 98 to the chamber 302, thus a relatively low pressure exists in the chamber 302, and there is a relatively big pressure drop at the valve 78 and therefore the rate of flow past the valve 78 is at its maximum. This provides the automatic rich mixture. As the fuel flow increases through the venturi 48 the fuel flow eventually reaches a value at which the engine will require an excessive quantity of fuel to prevent overheating. This is particularly true of air cooled engines which constitute 98% of the engines in use in the air. When this critical fuel flow is reached the valve 56 moves to the right and a small quantity of additional fuel, that is, the quantity which can flow through the restricted passage 264, is added to the fuel flowing past the restriction 78.

When the valves 254 and 184 are both moved counterclockwise, approximately 45°, the full pressure difference created by the venturi 48 becomes effective and therefore the valve 56 opens at a lower fuel flow. The reason for this is that when running at the automatic lean mixture the danger of overheating is greater and therefore the extra fuel is needed sooner and in larger quantities. This larger quantity is provided because both the restrictions 264 and 265 are now available for giving the necessary additional fuel. When the valve 184 is moved 45° anti-clockwise, into the automatic lean position, passage 182 provides a restricted communication between the passage 388 and the passage 98, so that a somewhat higher pressure is created in the chamber 302 so that the pressure drop across the valve 78 is reduced by this means and less fuel flows past the valve 78.

Temperature control

When the temperature rises the valve 284 moves down. Passage 400 is placed in communication with the passage 500. Pressure in the chamber 302 increases. This increases the pressure in the pipe 98. Thus the pressure in chamber 302 is increased which reduces the pressure drop across the valve 78, which reduces the fuel flow.

What I claim is:

1. A fuel supply means for an internal combustion engine having an inlet manifold and an air entrance leading thereto, comprising a fuel pump, a fuel outlet, a fuel return bypass connecting the fuel outlet with the fuel entrance, a variable pressure relief valve located in said return bypass, a moving wall connected to said valve so as to be responsive to the pressure drop at said valve, engine speed responsive means connected to said moving wall so as to regulate the said pressure drop so that as the engine speed increases the pressure drop increases and the pressure in said fuel pump outlet increases, a movable metering restriction in said fuel outlet, means responsive to the manifold air pressure connected to said movable metering restriction to open said metering restriction as said manifold air pressure increases, a second pressure regulating valve, said valve being located downstream from said movable restriction, a moving wall connected to said regulating valve, one side of said moving wall being subject to the fuel pressure downstream from said movable restriction, a chamber on the other side of said moving wall, a passage connecting said chamber to the downstream side of said pressure relief valve.

2. A device as set forth in claim 1 in which there is a restriction in the last mentioned passage where it communicates with the downstream side of said pressure relief valve and in which there is a temperature responsive element located in the inlet manifold and a flexible temperature responsive element connected thereto, a second passage transmitting the pressure created in the outlet from said pump to said chamber, a valve located in said passage connected to said flexible temperature responsive element so that the pressure in said chamber tends to increase at high temperature.

3. A device as set forth in claim 1 in which there is an element responsive to the difference between manifold air pressure and the engine exhaust back pressure associated with the means responsive to the manifold air pressure so that the movable metering restriction tends to open as the back pressure of the engine exhaust decreases.

4. A device as set forth in claim 1 in which there is a low speed fuel bypass around said movable metering restriction, a normally closed low speed fuel valve located in said bypass, a mechanical connection from said valve to said manifold air pressure responsive means whereby the low speed fuel valve is opened at abnormally low manifold air pressures.

5. A device as set forth in claim 1 in which there is a third pressure regulating valve, said valve being located in the fuel return bypass downstream from said speed controlled pressure relief valve, a moving wall connected to said valve, a chamber on the other side of said wall, a passage connecting said chamber with the fuel entrance yielding means in said chamber engaging with said moving wall.

6. A device as set forth in claim 1 in which there is a restriction in the last mentioned passage where it communicates with the downstream side of said pressure relief valve and in which there is a temperature responsive element located in the inlet manifold and a flexible temperature responsive element connected thereto, a second passage transmitting the pressure

created in the outlet from said pump to the chamber mentioned in claim 1, a valve located in said passage connected to said flexible temperature responsive element so that the pressure in said chamber tends to increase at high temperatures, and in which there is a third pressure regulating valve, said valve being located in the fuel return bypass downstream from said speed controlled pressure relief valve, a moving wall connected to said valve, a chamber on the other side of said wall, a passage connecting said chamber with the fuel entrance yielding means in said chamber engaging with said moving wall.

7. A device as set forth in claim 1 in which there is an element responsive to the difference between manifold air pressure and the engine exhaust back pressure associated with the means responsive to the manifold air pressure so that the movable metering restriction tends to open as the back pressure of the engine exhaust falls, and in which there is a third pressure regulating valve, said valve being located in the fuel return bypass downstream from said variable pressure relief valve, a moving wall connected to said valve, a chamber on the other side of said wall, a passage connecting said chamber with the fuel entrance yielding means in said chamber engaging with said moving wall.
